UNITED STATES PATENT OFFICE.

ABRAHAM L. BUSH, OF HOBOKEN, NEW JERSEY.

RAILWAY CONSTRUCTION.

No. 905,645.

Specification of Letters Patent.

Patented Dec. 1, 1908.

Application filed January 24, 1908. Serial No. 412,428.

To all whom it may concern:

Be it known that I, ABRAHAM L. BUSH, a citizen of the United States, residing at Hoboken, in the county of Hudson and State of New Jersey, have invented a new and useful Improvement in Railway Constructions, of which the following is a specification.

This invention relates to railway track constructions in which the running or track rails are supported on short supports or blocks which rest on a concrete road bed or foundation.

The object of this invention is to produce a track construction in which the rail supports can be easily removed and replaced, which is durable and reliable, and avoids undue rigidity.

In the accompanying drawings: Figure 1 is a vertical cross section of the track construction in line 1—1, Fig. 3. Fig. 2 is a top plan view of one of the rail supporting blocks. Fig. 3 is a top plan view of the track construction. Fig. 4 is a longitudinal section through the guard rail in line 4—4, Fig. 3. Fig. 5 is a perspective view of a rail supporting block and filling piece connected by staples.

Like reference characters refer to like parts in the several figures.

10 represents the rock or earth on which the road is constructed and 11 the concrete bed or foundation laid thereon and reinforced, if necessary, in any suitable manner.

12 represents wooden supporting blocks arranged in the concrete bed and projecting above the same so as to support the running or track rails 13 clear of the concrete bed. Each block is arranged under one rail only and is seated in a recess or depression in the concrete bed, which recess is closed at its inner end and opens outwardly. The block rests with its inner end against the closed inner end of the recess, whereby the block is held against inward movement. The block is held against outward movement by an outwardly facing shoulder or offset 15 formed on one side of the block and bearing against an inwardly facing shoulder 16 in the side of the recess. The shoulder is formed on the block by reducing the width of the outer portion of the block and the width of the outer portion of the recess in the concrete bed is correspondingly reduced.

17 The opposite side of the block is straight and is engaged by a wedge or filling piece

17 which is inserted between the straight side of the block and the adjacent side of the recess in the concrete bed. This filling piece or wedge is of such width in the longitudinal direction of the track that in the absence of this piece the block can be moved in the recess lengthwise of the rail far enough to disengage its shoulder 15 from the shoulder 16 of the recess, leaving the block free to be removed from under the rail through the open outer end of the recess.

The rails are secured to the blocks by any suitable fastening devices, for instance, by tie plates 18 and lag screws or screw spikes 19.

21 represents wooden guard rails which extend over the blocks and filling pieces along the outer marginal portions of the concrete bed to which they are secured by anchor bolts 22. The blocks may be connected to the guard rails by lag screws 23 and the wedges or filling pieces can be connected to the guard rails by lag screws 24. When no guard rails are employed the wedges or filling pieces can be secured in position by staples 25 which are driven into adjoining portions of these pieces and the blocks, as represented in Fig. 5.

The wedges or filling pieces can be tightened when necessary to take up any looseness arising from shrinkage or wear. When it is necessary to renew a block, the fastenings of the rail, the block and the wedge are released, the wedge is withdrawn and the block is withdrawn from under the rail. A new block is then inserted under the rail, the wedge is driven home and the fastenings are again applied, as described. This operation can be readily performed by one man and does not in any way interfere with the traffic.

In constructing the track the blocks and wedges can be arranged in the concrete bed in molding the latter. As the tie blocks rest on a solid concrete bed there is no heaving of the track from frost in winter or settlement by lack of drainage. The maintenance in tunnels and subways of ordinary ballasted track in which the rails rest on cross ties is very expensive and difficult and also dangerous to the track men, and the removal of one of the cross ties requires a gang of men and makes it necessary to protect the traffic while the work is being done. The wooden supporting blocks of the described construction are easily removed and replaced,

as stated, and supply sufficient yielding qualities to the track to avoid undue rigidity and are not subject to the rapid deterioration to which metallic supports are liable in tunnels and subways from engine gases and moisture.

I claim as my invention:

1. In a railway track construction, the combination of a concrete bed having a recess transverse to the track, opening outwardly at the side of the bed and provided with a plane bottom, a removable supporting block provided with a plane bottom and seated in said recess, means for securing the block in said recess arranged between opposing sides of the recess and block, and a track rail supported on said block, substantially as set forth.
2. In a railway track construction, the combination of a concrete bed having a transverse recess which opens outwardly at the side of the bed, a supporting block seated in said recess and movable therein both from side to side of the recess and inwardly and outwardly, securing means for the block arranged between opposing sides of the recess and block, and a track rail supported on said block, substantially as set forth.
3. In a railway track construction, the combination of a concrete bed having an outwardly opening recess, a supporting block arranged in said recess, said recess and said

block being provided on one side with interlocking shoulders, a removable filling piece arranged between the opposite side of said recess and said block, and a track rail supported on said block, substantially as set forth.

4. In a railway track construction, the combination of a concrete bed having an outwardly opening recess, a supporting block arranged in said recess, a filling piece arranged between adjacent sides of said block and said recess, a guard rail secured to said concrete bed and extending over said block and filling piece, and a track rail supported on said block, substantially as set forth.

5. In a railway track construction, the combination of a concrete bed having an outwardly opening recess provided on one side with an inwardly facing shoulder, a supporting block arranged in said recess and provided on the corresponding side with an outwardly facing shoulder, a filling piece arranged between the opposite side of said recess and said block, and a track rail supported on said block, substantially as set forth.

Witness my hand in the presence of two subscribing witnesses:

ABRAHAM L. BUSH.
